UNITED STATES PATENT OFFICE.

J. BENNETT WALLACE, OF CHICAGO, ILLINOIS, ASSIGNOR TO THE MYERS
MANUFACTURING COMPANY, OF SAME PLACE.

PLUMBER'S HEATER.

SPECIFICATION forming part of Letters Patent No. 319,868, dated June 9, 1885.

Application filed June 9, 1884. (No model.)

To all whom it may concern:

Be it known that I, J. BENNETT WALLACE, of Chicago, in the county of Cook and State of Illinois, have invented certain new and useful Improvements in Plumbers' Heaters; and I do hereby declare that the following is a full, clear, and exact description thereof, reference being had to the accompanying drawings, and to the letters of reference marked thereon, which form a part of this specification.

This invention relates to portable furnaces of a class used by tanners and plumbers, and concerns the structure both of the reservoir and of the burner.

The invention consists in the matters hereinafter set forth, and pointed out in the appended claims.

In the drawings, Figure 1 is a central vertical section of the entire structure in the plane of the line $\alpha\alpha$ of Fig. 2. Fig. 2 is a top or plan view of the burner, and of the ring located at the top of the burner for the support of the article to be heated. Figs. 3 and 4 are detail views.

A is the reservoir as a whole; B, the burner, and C a ring or annular frame supported at the top of the burner, for the purpose of sustaining either directly or indirectly the article to be heated.

The reservoir A consists of the cylindric or conical side rim, A', and bottom a^4 , joined by a marginal seam and solder, or otherwise, as may be desired. Said reservoir also embraces the top A², which is of cast-iron and fitted to the top of the rim A', usually by means of an annular groove receiving the upper edge of the rim A', as shown in Fig. 1; but, if desired, one wall of the groove may be absent, leaving either an inner or an outer flange adapted to fit within or over the edge of said rim A'. A tight joint is provided at the juncture of the top plate, A², with the rim A' by means of solder.

For the purpose of giving additional strength to the reservoir, particularly when the rim A' and bottom a^4 are of sheet metal, I prefer the construction further shown in said Fig. 1. In the said construction just referred to, A³ is a flanged interiorly-threaded nut applied to a central aperture in the bottom a^4 , and A⁴ is a tube or rod threaded into said nut A³ and into

a central hub or boss in the top plate, A². In this said construction, also, a marginal rim, a^6 , of cast-iron, is employed, which surrounds the lower marginal angle of the reservoir, and which is preferably connected with the nut A³ by radial arms a^5 . A body of solder applied around the nut A³, as indicated in heavy black in Fig. 1, serves to make a close joint between the aperture in the bottom a^4 and said nut, and generally I prefer to apply solder around the margin of the bottom a^4 at its junction with the rim a^6 .

The reservoir is provided with an inlet-tube, a , cast in the top plate, A², and interiorly threaded in a familiar manner to receive the close-fitting screw-stopper a' . In said top plate, A², is also set a tube, a^2 , provided with a stop-cock, a^3 , through which air may be injected for the purpose of applying pressure to the liquid without the reservoir, in order to force the same to the burner.

The burner B is contrived with a special view to obtaining a greater generating efficiency; and to this end it is provided with the passage or tube B⁷, extending centrally across the interior of the open vapor-tube B⁸, and is otherwise constructed as will be further explained. Said burner is made, as here shown, in a single casting, in which the passages are formed preferably by drilling. It has the primary induction liquid-tube B' connected with the top plate, A², of the reservoir, either directly or by means of the coupling b , and prolonged within said reservoir by the extension tube b', leading nearly to the bottom of the latter. The passage of the vertical tube B' is continued horizontally around the head B² in the direction indicated by the arrows in Fig. 2. Said passage within the head B² extends entirely around the central opening or vapor-induction passage of the burner to a point opposite the passage B', at which point it descends a short distance, as shown in Fig. 1, and then takes the horizontal course through the tube B⁷ to the opposite side of the burner, whence it is prolonged in the vertical tube B³ and lateral projection B⁴ thereof to the central head, B⁵, which contains the needle-valve b². Said needle-valve is arranged in the axis of the open vapor-tube B⁸ in the usual manner, and is preferably threaded into the head B⁵ by a

high-pitched thread, as shown, so that the desired opening of said valve may be effected by only a partial rotation thereof. To turn the valve, the lower end of its shaft is provided 5 with a laterally-projecting lever, b^3 , adjustably secured by a set-screw. The shaft of the valve is packed by a cap, b^4 , surrounding the same and threaded upon the lower end of the head B^5 . A drip-cup, b^5 , of the ordinary construction, is secured on said head by the packing cap-nut b^4 .

Just below the head B^2 the vapor-tube B^8 is provided with opposite horizontal slots, b^6 , which allow a portion of the vapor from the 15 needle-valve to escape and to pass upward externally to the head. This portion of the vapor ignites at the slots b^6 , or without the tube B^8 , while that portion of said vapor which rises through the central opening of the head ignites in said opening or within the said tube B^8 . As a result, flames are made to more perfectly embrace the passages leading from the 20 liquid-induction tube B' to the needle-valve than heretofore; or, in other words, a greater 25 extent of external surface of these passages is exposed to the flames with the effect of materially increasing the generating capacity of the burner.

The tube B^7 , traversing the passage of the 30 vapor-tube B^8 , not only serves the purpose set forth and resulting from its forming part of the generating or interior vapor-passage of the burner, but it has also the useful effect of so retarding the movement of the vapor 35 through the open tube B^8 , and thereby prevents the flame from being extinguished or from self-extinguishment when the pot or article being heated is removed from the burner. This latter effect will of course be 40 equally accomplished if the traversing part is a mere bar, or if it is not a tube or a part of the interior vapor-passage.

B^6 is a large tube, which embraces the entire burner and extends from a point sufficiently high at the bottom to freely admit air 45 to the level or a little above the level of the burner-top. The presence of this tube serves to produce air-currents, which concentrate the exterior and interior flames of the burner 50 above the burner-top, causing them to still more perfectly embrace the interior passages of said burner and giving a single flame above the burner in form for effective working purposes.

55 The tube or shield B^6 may be supported in any suitable manner, either from the top plate of the reservoir, from the burner, or from the ring C . The last mentioned is the construction herein shown, three inwardly-directed arms, C^2 , being cast on said ring, upon the inner and rivet-formed ends of which projections b^7 on the tube B^6 are secured.

The ring or frame C is upheld in suitable 65 position by rods or standards C' , screwed into the reservoir top plate, A^2 , and connected with

inwardly-projecting lugs c on said ring. The utensil to be heated is placed on said ring. When heating a pot, a cage or shield, C^3 , is desirably employed to prevent deflection of the 70 flame by the wind. This shield is movably attached to the ring by pins c' , fixed in the ring, and notched projections c^2 on the shield, forming, essentially, what is known as a bayonet-connection and operated in a familiar 75 manner.

A bail, C^4 , pivoted to the ring C , serves for transporting the implement from place to place.

I am aware that a hydrocarbon-burner has 80 heretofore been constructed with a circular plate or casting provided with an interior vaporizing or generating chamber, and located centrally at the upper end of a vapor passage or chamber, so as to form with said chamber 85 an annular outlet for the flame, and I do not, therefore, claim, broadly, a generating chamber or passage located within a vapor-tube; but my invention, as it relates to the device referred to, is restricted to a construction embracing a vapor-tube open at both ends, and provided with a transverse bar adapted to retard the passage of vapor through the tube, as set forth in the appended claims.

I claim as my invention—

95 1. The combination, with the cast-iron top plate, A^2 , and sheet-metal sides and bottom of the reservoir, of a nut, A^3 , and rim a^6 , connected by arms a^5 with said nut, and a connecting rod or tube, A^4 , substantially as described.

100 2. The combination of the centrally-open burner-head provided with an interior passage extending around the opening of said head, the open vapor-tube, the liquid-induction tube leading into the passage within the head, the transverse tube leading from said passage across the open vapor-tube, and a passage leading from said cross-tube to the needle-valve, substantially as described.

105 3. The combination of the centrally-open burner-head provided with an interior passage extending around said opening, the open vapor-tube provided with slots below the head, the needle-valve, the liquid-induction tube 115 leading into the passage within the head, the transverse tube leading from said passage across the open vapor-tube, and a passage leading from said cross-tube to the needle-valve, substantially as described.

110 4. The combination, with the burner B , having an open vapor-tube, B^8 , provided with lateral openings b^6 , of a shield surrounding the burner, substantially as and for the purposes set forth.

115 In testimony that I claim the foregoing as my invention I affix my signature in presence of two witnesses.

120 J. BENNETT WALLACE.
